Specification of Letters Patent.

Patented Jan. 8, 1918.

Application filed June 5, 1913. Serial No. 771,848.

To all whom it may concern:

Be it known that we, LEON E. LABOMBARDE and MELVIN H. SIDEBOOTHAM, citizens of the United States, and residents of Nashua, in the county of Hillsborough and State of New Hampshire, have invented certain new and useful Improvements in Envelop-Machines, of which the following is a specification.

10 This invention relates to the manufacture of folded paper receptacles, and has particular reference to the making of such receptacles in the form of what are usually called envelopes, the specific shape made by the machine illustrated being vertically elongated and consequently similar to a paper bag having a top flap which may be folded down by hand after the receptacle has been filled.

One of the objects of the invention is to 20 provide a machine that will be continuous and rapid in its operation, there being no pause or hesitation in the travel of the blanks except at the moment when the direction of travel is changed, the machine employing 25 only constantly and rapidly moving carriers which cause the blanks to travel by friction, so that said blanks will pass through the machine and be folded without possibility of interference with each other at the transfer 30 point.

Another object of the invention is to provide means which will insure the accurate entrance of the blanks to the folding mechanism, without the employment of guides.

35 Further objects are to provide improvements which will be hereinafter explained.

To these ends, the invention consists in the construction and combination of parts substantially as hereinafter described and 40 claimed.

To aid in understanding the accompanying drawings, we will first explain that our present machine comprises primary and secondary folding mechanisms, each of which 45 is similar in construction and operation to the box-making machine for which U. S. Letters Patent 960,348, were granted June 7, 1910, but with certain differences herein-after explained, said two folding mechanisms being at a right angle to each other with connecting intervening transfer mechanism, which latter mechanism includes one of the principal features of our present invention.

Figure 1 is a plan view of a portion of the 55 primary folding mechanism.

Fig. 2 is a plan view of the remaining portion of the primary folding mechanism, and of the transfer mechanism, and of a portion of the secondary folding mechanism. 60

Figs. 1 and 2, taken together, represent in plan, the entire machine, omitting unnecessary details, and also omitting the delivery portion of the secondary folding mechanism, because it is practically a duplicate of the 65 delivery end of the primary folding mechanism.

Fig. 3 is an elevation of a portion of the machine shown in Fig. 1.

Fig. 4 is an elevation of a portion of the 70 mechanism shown in Fig. 2.

Fig. 5 is a detail sectional view of the feed mechanism which forwards to the secondary folding mechanism the blanks which have been partly folded by the primary folding 75 mechanism.

Fig. 6 is an elevation of a portion of the machine shown in Fig. 3, looking from the other side, Fig. 6 being on a somewhat larger scale. 80

Fig. 7 is a detail sectional view of one of the feed chains.

Fig. 8 is a detail elevation, looking in the direction of the arrow 8, in Fig. 2.

Fig. 9 is a detail perspective view of one 85 of the pin-carrying brackets attached to the feed chains.

Figs. 10, 11 and 12 are detail views of a form of combing feed roll which may be employed. 90

Similar reference characters indicate similar parts in all of the views.

Different portions of the frame of the machine are indicated at 10, said frame having at one end (Figs. 1 and 3) an adjustable inclined table 11 for the blanks, which may be of any desired and practicable quality and thickness of paper. The table is pivoted at 12 to the frame and at 13 to the upper end of a strut or rod 14, the lower end of which is slidably clamped in a sleeve 15 pivoted at 16. A pile of blanks *a* placed on the table will be fed one at a time by mechanism practically the same as in U. S. Patent 540,131, granted May 28, 1895, to Allen, said mechanism comprising one or more wheels 17 secured to a continuously operating shaft 18, each wheel having a section of friction ma- 95 100 105

terial 19, such as rubber, to draw off and feed the top blank of the pile, the blanks below the top one having their front edges in contact with one or more retarding devices such 5 as sections of rubber 20 carried by hinged members 21 adjustable by screws 22.

Each blank as it is fed by the wheels 17 is deposited upon forwarding tapes or belts 23 running on elongated rolls or shafts 24, 10 25. Instead of the tapes or belts 23 being traveling belts, they might be stationary, if of frictionless material such as smooth metal. When blanks of very thin material are being fed through the machine, it may be preferable 15 able to have the supports such as the belts 23 move. Since the blanks, however, are really fed by the chains 26, and pins herein-after described, the only particular essential is that the blank shall be supported on a surface 20 face so that they will be fed along by the chain pins. The chains are mounted upon sprockets 29 carried by shafts 27, 28, (see Figs. 1, 3, 6 and 7). Further description of the operation of the chains and their pins 25 will be given hereinafter. Each blank advanced by the chain pins passes between shafts 31, having male and female scoring rolls 32, adjustably secured lengthwise of said shafts, to crease the blank on lines such 30 as indicated at a' , in Fig. 1, which figure indicates two of the blanks by dotted lines, as traveling through the machine, one of said dotted line representations of a blank having the score lines and flaps designated as 35 hereinafter described. The lines a' define the side or longer edges of the completed envelop.

Each blank next passes between upper and lower coating carriers comprising belts 40 33, 34, mounted on pulleys which are adjustable toward and from each other on their shafts. The wide flaps a^2 of the blank project beyond the carriers, and as it passes along, the under surface of one flap, near 45 its edge, receives a stripe of an adhesive from a glue wheel 35. Next, the flaps a^2 are turned upwardly on their score lines a' by inclined or twisted folders 36, which, although adjustable, are preferably rigid. 50 For convenience of distinguishing description they are referred to herein-after as rigid folders. The upturned flaps are next folded inwardly, one over the other (the one having the stripe of adhesive being folded, 55 of course, in advance of the other) by twist belts 37. Suitable shoes or pressing devices are employed to insure the proper advance of the blank, without twisting, while passing from upper belts 33 to the point where 60 the portions of the twisted belts 37 will grip the infolded edges of the blank between them and the lower carrier belts 34. Edge guides also may be employed. The details of the carrying, folding and guiding 65 devices need not be illustrated or further

described herein, as they are disclosed and claimed in the Patent 960,348, above referred to, the structure being substantially the same in the present machine.

From the folder belts 37, the blank passes 70 between pressing rolls 39 (Fig. 2) adjustably secured to their shafts 38 substantially as in the said patent. The blank next passes on to a series of tapes 43 mounted upon pulleys carried by shafts 44, 45, (see Figs. 75 2, 4, and 6), said blanks being carried by the tapes against the stop plate 46. To prevent the blanks from rebounding when they contact with the stop 46, we provide a series of spring-holders 40, secured to a transverse 80 rod 41, which is suitably supported so that the inclined ends of the spring-holders 40 will be held in position to lightly bear upon the edge of each blank coming in contact with the stop 46. Each blank that is delivered by the primary folding mechanism on to the tapes 43, reaches position against the stop 46, with one edge in contact with a guide 42, the position of the blank being indicated by dotted lines in Fig. 2, in the 85 position which it momentarily occupies when arrested, one folded edge being in the position indicated in Fig. 5, to be grasped between the transfer starters 47 and a roll 48 (Figs. 2 and 5), and started in their new 90 direction of movement by a drawing or pulling action. The starters 47 are carried by a rotary shaft 49 and have their ends formed or provided with segments having friction material facings or pins, or both, to engage 95 the upper surface of the folded edges of the blank projecting from the tapes, said starters being timed as to their operation so as to engage said blank the instant of or after its arrival in arrested position and start it 100 in its new direction of travel indicated by the arrow in Fig. 2. To enable the starters to be accurately timed as mentioned, they are adjustable on the shaft 49. As shown 105 in Fig. 2, the hub of each starter 47 has a 110 set screw passed through it. This set screw binds against shaft 49. Therefore, either starter may be secured in any desired position longitudinally of the shaft according to the size of the blanks, or rotatively on the 115 shaft so that one may coöperate with roll 48 (Fig. 5) in advance of the other when such adjustment is necessary to insure forwarding of the blanks without liability of being turned askew. These starters 47 act 120 only for a moment, to introduce the blanks between rolls 55 and the carrier belts, and then leave the blanks. Therefore no special care need be exercised regarding the speed 125 of travel of the blanks after reaching said rolls and belts. If pushing devices were used to remove the blanks from the transfer table (tapes 43), accurate uniformity of speed would be necessary. For instance any excess of speed of the pushing devices over 130

that of the said rolls and belts would tend to crumple up or dislodge the blanks. Furthermore, when blanks are being pushed at high speed, they are liable to have their 5 front edges deflected by the resistance of the atmosphere. Such deflection can not occur with my devices which merely start the blanks the forward edges of which are close to the short belts which deliver to the 10 carrier belts 62, 63, as illustrated in Fig. 5. The starting devices are in operative engagement with each blank, for a distance of travel of the blank that is but a fraction of the distance of movement imparted to 15 the blank by the said short belts which constitute mechanism independent of said starting devices for delivering to the secondary folding mechanism those blanks which are set in motion by said starting devices. The 20 transfer starters 47 are so located in positions lengthwise of their revolving shaft as not to contact with any pulleys or rolls. To insure uniform peripheral speed of the transfer starting members, the shaft 49 is 25 provided with a gear 52 meshing with a pinion 53 of roll 48. To guide the blanks to the roll 48, one or more of the belts 62 extends closer to said roll than the others, such extension being indicated at 54 in Fig. 30 2, mounted on a roll on a shaft 55 (Fig. 5). Of course, the companion belt 63 is similarly extended, as shown in Fig. 5.

Each blank pulled away in the new direction is acted upon by mechanism similar to 35 that which delivered it to the transfer mechanism, to fold over the remaining flaps α^3 , α^4 , which constitute the bottom and top end flaps respectively, of the bag-shaped envelop, but with a difference that the adhesive 40 for flap α^3 is applied to the upper surface, instead of the under surface, as the blank travels. The blank in the partially folded condition is started by the transfer members 47, 48, between male and female 45 scoring rolls 59 carried by shafts 60, and between upper and lower carrier belts 62, 63, mounted at one end upon pulleys 56, carried by shafts 57, said shafts being geared to rotate in unison, as by the intermeshing gears 58. The carrier belts 62, 63, forward the partially folded blanks through 50 secondary folding mechanism, including rigid inclines 67 and twisted folders, the complete secondary folding mechanism not 55 being illustrated herein, as it includes twisted folding belts and other parts similar to the portions of the primary folding mechanism illustrated herein, and also similar to the machine of the said Letters Patent 60 960,348. As the blank moves along between carrier belts 62, 63, its flap α^3 receives a stripe of adhesive on its upper surface, from a roll or disk 68, carried by a suitable shaft. As the adhesive-applying mechanism is not claimed herein, further refer-

ence thereto is unnecessary. The flaps α^3 , α^4 , (Fig. 1), projecting outside of the nip of carrier belts 62, 63, are turned upwardly along the score lines α^5 by the inclined rigid folders 67 which are similar in construction 70 and operation to the rigid folders 36 of the primary folding mechanism. If it should not be desired to fold the flap α^4 , one rigid incline 67 and one twist belt may be omitted.

It is to be understood that the machine is 75 capable of making envelops of various shapes and sizes other than the one illustrated. The different parts are adjustable for different sizes, the width of the folding members apart being varied by screw adjustments such as shown in Fig. 14, of the Patent 960,348.

The machine may be driven by a belt capable of being shifted from one to the other of the fast and loose pulleys 69, 70, (Fig. 4). 85 The various shafts and gearing for transmitting motion from the shaft of pulleys 69, 70, to the different mechanisms of the complete machine are indicated in the drawings, but will not need to be described, as 90 we do not claim herein any particular means for carrying motion from one part of the machine to another. The connections are such, of course, that the various coacting carrying members all move with the same 95 rate of speed, to cause the blanks to travel rapidly, evenly and continuously, the only pause being when they reach stop 46. The rate at which the primary feeders 19 cause the blanks to follow one another from the 100 pile on the table is such that there will be sufficient space between the blanks reaching the transfer mechanism to prevent a partially folded blank from so overlapping the preceding one as to interfere with the said 105 preceding one being drawn away by the transfer feeders 47.

By means of any suitable speed change mechanism, or change speed gears, the primary and secondary feeders may be varied 110 as to their speed of action, according to the sizes of the blanks to be folded, in order to secure proper spacing between them. In practice, the carriers of the secondary folding mechanism preferably travel at less 115 speed than those of the primary folding mechanism. This is because the articles going through the secondary mechanism are smaller (in the direction of travel), due to their being partially folded by the primary 120 mechanism. As there is no need then for any greater spacing between blanks in the secondary than in the primary, the secondary can operate at the lower speed mentioned, and to reduce wear and tear of its 125 parts, and also to avoid delivering the articles to the stacker or counter at an excessive speed.

As the material of which the envelops are made is quite thin, we have produced a feed 130

or comb wheel 17 especially adapted for thin work, although it is also very desirable for thick work. For thick or thin blanks, it provides for preventing the passage of more than one blank at a time, and also provides for adjustment to take up wear of the friction surface, so that, when rubber is used, the roll can be used until the facing is worn almost through.

10 Referring to Figs. 10, 11, and 12, the wheel 17 has an annular recess presenting two edge portions 72 between which the elastic rubber ring or periphery 19 is mounted, said ring projecting slightly beyond or 15 outside of the edges 72. The rubber of which the ring 19 is made is preferably softer than the retarder or retarders 20 (Fig. 3). Inside the ring 19 are metal segments 73, the adjacent edges of the segments 20 being beveled and slightly spaced, as shown in Fig. 12. Each segment is carried by a radially adjustable pin 74 (Fig. 10) having a cone-shaped inner end. Mounted slidably on the hub 75 of the wheel is a ring 76 having 25 a series of projections 77 provided with beveled or cam faces. For convenience, these projections are referred to as cams. The wheel is formed with transverse apertures along which the cams can be adjusted 30 by means of two or more screws 78 passing through the ring 76 into the body of the wheel, so that the cams 77 can be adjusted to force the pins 74 radially outward, increasing the diameter of the circle formed 35 by the segments and stretching the ring 19 to compensate for wear.

In practice, the wheel 17 is so mounted and the retard 20 so adjusted, that the space between the retard and the edges 72 of the 40 feed wheel will permit but one blank at a time to pass, the retard being of material sufficiently hard (as relatively hard rubber) to not yield and let the edge of a second blank enter the space. The ring 19 is expanded just enough to project beyond the 45 edges 72 and perform its combing or feeding action. As it wears, the ring is expanded, and this can be done until the ring is worn down to an eighth of an inch or less.

50 By removing all but one of the segments, the ring will project in but one place, the rest of the ring lying in the recess from which the segments are removed, thus providing an intermittently operating feeder which will 55 comb off a blank only each time the projecting portion of the ring acts on the pile of blanks. Or only the one remaining segment can be faced with rubber and such segment or its pin provided with means, as a set 60 screw, for preventing it from escaping from the wheel. In Figs. 10 and 11, such a set screw is indicated at 79 for each pin 74. Such set screws are desirable to prevent the segments from dropping out when the ring 65 19 is removed, or if it should be worn down

so as to break during the running of the machine. Such set screws will, of course, be loosened when the ring 76 and its cams are to be adjusted. Whether one or all segments are used, there will be one or more 70 edge portions 72 to constitute a gage to prevent the entry of a second blank between the wheel or segment and retard until the first has passed.

It will thus be seen that we have provided 75 a feed wheel which is convertible so as to constitute an essential portion of timed feed mechanism, or straight top feed mechanism. If the yielding peripheral portion of the wheel be caused to project in but one place, 80 as indicated in Fig. 3, a blank will be taken from the top of the pile on the table only once for each rotation of the shaft of the combing wheel, the blanks then being sent through the machine being spaced according 85 to the circumference of the combing wheels. If the yielding peripheral portion be caused to project at two diametrically opposite places, then the combing wheels are adapted to operate on smaller blanks so as to remove 90 two blanks from the pile for each rotation. If the yielding peripheral portion be presented uniformly, as shown in Fig. 11, then a feed of a blank will occur from the top of the pile each time that a preceding blank is 95 removed. In other words, the blanks will follow each other with the front edge of one close behind the rear edge of the preceding one, this being known as the straight top feed, instead of a timed feed.

The table 11 is preferably provided with 100 guides such as the flanges 80 (Figs. 1 and 3) rising from straps 81 which are adjustable laterally of the table and held as by means of set screws 82.

Suitably supported by the frame of the machine are uprights or posts 83 (Figs. 3, 6 and 7) having brackets 84 in which are mounted transverse rods 85, said rods having depending brackets 86 in which are 110 mounted two longitudinal rods 87 (Fig. 1). Pendent brackets 88, adjustable along the rods 87, provide bearings for the shaft 27 of the feed chains. The shaft 28 may be similarly supported by brackets depending 115 from rod 85. This structure not only provides for lateral adjustment of the feed chains, but also enables them to be accurately adjusted in a direction longitudinally of the machine to enable the pins of the 120 chains presently described to properly engage each blank in the four reentrant angles presented by the edges of the flaps a^2 , a^3 , a^4 .

In Fig. 9, is shown a bracket 89 having a flange 90 provided with a slot 91 for the 125 screw 93, the end of the screw projecting through the slot having secured thereto a cylindrical member 92, which for convenience of description, is referred to herein as a pin. Each chain 26 has secured to it at 130

substantially equal distances along its length, four brackets 89, so that each chain will carry four pins 92. By means of the slots 91, the pins 92 can be adjusted in a direction 5 lengthwise of the chain. The brackets 89 may be attached anywhere along the chain. This feature of our invention enables us to cause the four reënterant angles of each blank to be accurately engaged by four pins. Since 10 each of the two chains has four pins, it provides, of course, for the two chains advancing two separate blanks, one after the other, for each complete cycle of movement of the chains. The chains are of such length, and 15 the relative locations of the pins 92, and the timing of the feed of the blanks, bear such relationship to each other, that the front edge of each blank arrives on the belts 23 just in time to touch, or almost touch the 20 rear surfaces of two pins 92 carried by the two chains, so that two more pins 92 will engage the rear edge of the blank, as indicated in Fig. 7, so as to push the blank up against the first-mentioned two pins, if the 25 blank was not deposited in just the right position to contact with the forward pins. Fig. 7 illustrates two dotted line positions of a pin 92. This is merely to show how the pins 92 will pass down behind the rear edge 30 of a forwardly moving blank. When the rear edge of a blank is in the position indicated at x in Fig. 7, the pins 92 will be substantially in the position x , and as the blank advances so that its rear edge is in the position 35 y , the pins 92 have reached the position y . As the parts move to the full line position of Fig. 7, the pins engage the rear edge of the blank and push it up against the forward or front two pins, the result being that 40 the blank is then firmly held at four points, and is started through between the scoring rolls and started into the primary folding mechanism, in perfectly squared position, without requiring any side guides or other 45 means for causing them to enter the scoring or folding mechanism accurately. The feeds 19 so engage the blanks that they cannot start very much askew, but they are sometimes liable to be sufficiently twisted to interfere 50 with the accurate production of envelopes. But since the two rear pins straighten each blank up against the front two pins, and then carry the blanks forward, held in such manner that they cannot possibly 55 turn, the machine can operate so as to advance the blanks very rapidly, because each blank is positively held at four points. As a matter of fact, instead of traveling tapes 23 being employed, they might be 60 smooth stationary surfaces, so far as having any effect upon the accuracy of the position of the blanks is concerned. A blank engaged by the four pins 92 as described, cannot get twisted or askew, whether or not 65 any tapes 23 are employed. It is essential,

of course, that there will be some supporting surface for the blanks, but that is practically all.

Referring to Figs. 2 and 8, when the partly folded blanks which have passed 70 through the primary folding mechanism are delivered between the rolls 39, they must be accurately squared up before the transfer feeders 47 start them in their new direction. To this end we provide the stops 46 and the 75 guide 42. It is essential that each blank shall pass to its position against the stop 46, squarely up against the guide 42. To this end we provide a series of rolls 94, which, for convenience of description, are referred to as 80 deflecting rolls. Each roll is carried by a shaft 95 supported by a bracket 96 adjustably connected to a rod 95^a projecting from a block 97 in such manner that the axes of the rolls 94 may be adjusted, as indicated 85 in Fig. 2, two of the rolls shown in Fig. 8 being also shown as adjusted in such manner that the said rolls, which are idle ones, bearing upon the edge of the blank as it arrives upon the last tape 43, of the series, will be deflected against the guide 42 by said rolls 94. In other words, the idle pressure rolls 94 can be set at such an angle as to insure the blanks being deflected or directed squarely up against the 90 guide rib or bar 42. The blocks 97 are carried by a rod 98, which is adjustably supported at its ends to enable the parts to be adjusted for different widths of blanks. The adjustments in practice, must be such 100 that when each partly folded blank arrives and is squared up against the stop 46 and guide 42, the segments 47, which are properly timed as to their rotation, will then contact with the folded edge opposite that edge 105 which is against the guide 42, and pull the blank away to start it between the scoring rolls 59 and the secondary folding mechanism. It is to be understood, of course, that all of the parts to be adjusted for different 110 sizes of blanks, are capable of being so positioned as to retain the proper relationship of the coöperating mechanisms, in all phases of adjustment.

As has been stated, the belts or tapes 23 115 serve as the support, so that the blanks will be accurately and squarely forwarded by the four pins of the two belts engaging the reënterant angles of the blanks. Obviously, instead of employing belts or tapes, we may 120 employ a series of rolls, driven or idle. Or the blanks can be supported upon smooth stationary surfaces, the forwarding of the blanks being then caused by the chain pins, aided, if desired, by means of suitable rotary brushing devices, such devices being rotated in a direction to contact with the upper surfaces of the blanks and exerting friction thereon, to aid in advancing or forwarding the blanks. 125

To guide each blank which is advanced over the retarders 20, indicated in Fig. 3, on to the supporting surface 23, we employ one or more idle wheels or rolls underneath 5 the combing wheels 17, said idle wheels having smooth peripheries and having no feeding action. They constitute anti-friction devices to hold each blank in position to be operated upon by the feed 19 carried by the wheels 17. As hereinbefore stated, after each blank is started into the machine by the wheels 17, any suitable mechanism 10 may be employed for insuring their being carried to position to be engaged by the pins 15 92 of the chains.

It is to be understood, of course, that the 20 number of pins 92 carried by the chains 26, and their relative spacing along said chains, will be varied according to the number of 25 blanks (such as one or two) fed by each rotation of the shaft 18, and according to the sizes of the blanks being treated.

We claim:

1. A machine of the character specified, 25 comprising primary and secondary mechanisms for folding blanks on lines at an angle to each other, stops for arresting the blanks after leaving the primary folding mechanism, starting devices movable in a direction 30 toward the secondary folding mechanism, and independent mechanism for delivering to the said secondary mechanism blanks set in motion by the starting devices, said starting devices being in operative engagement 35 with a blank for a distance that is but a fraction of the distance of movement imparted by said independent delivery mechanism.

2. A machine of the character described, 40 comprising primary and secondary folding mechanisms at an angle to each other, an endless traveling platform for receiving the blanks from the primary mechanism, and rotary feeders adjacent that edge of said platform which is nearest the secondary 45 folding mechanism, said feeders being in position to receive an edge portion of the blank as it is delivered to the platform by the primary folding mechanism.

3. A machine of the character described, 50 comprising folding mechanism and means for delivering blanks thereto in accurate positions, said means comprising a support for the blanks, and endless pin-carriers having blank-engaging pins spaced to engage both 55 front and rear edge portions of the blanks on said support.

4. A machine of the character described, 60 comprising primary and secondary folding mechanisms at an angle to each other, and an intermediate transfer mechanism, each 65 of the folding mechanisms having blank carriers, stationary folders for turning flap portions of the blanks upwardly, twist belt folders for turning said flap portions from up- 70 ward to flat in-turned position to complete

the folding of said flap portions, and pressers between the stationary folders and the belt folders.

5. A machine of the character described, 70 comprising primary and secondary folding mechanisms at an angle to each other, and an intermediate transfer mechanism, each of the folding mechanisms having blank carriers, blank scorers, stationary folders for turning flap portions of the blanks upwardly, twist 75 belt folders for turning said flap portions from upward to flat in-turned position to complete the folding of said flap portions, and pressers between the stationary folders and the belt folders. 80

6. A machine of the character described, 85 comprising folding mechanism, means for delivering blanks thereto in accurate position, said means comprising four traveling pins spaced to engage each blank at four 90 separate points, and a timed feeder for supplying blanks accurately spaced to said traveling pins.

7. A machine of the character described, 90 comprising primary and secondary folding mechanisms at an angle to each other, an intermediate transfer mechanism, a timed feeder for the primary mechanism to supply blanks spaced to prevent interference 95 with each other at the transfer mechanism, means for arresting each blank as it arrives at the transfer mechanism, and a pair of intermittently operating devices to start each arrested blank and pull it toward the secondary folding mechanism, said devices 100 being independently adjustable laterally and also as to their relative time of operation.

8. A machine of the character described, 105 comprising folding mechanism and means for delivering blanks thereto in accurate positions, said means comprising four traveling pins spaced to engage each blank at four 110 separate points.

9. A machine of the character described, 110 comprising folding mechanism, a support in advance of said folding mechanism, and means for delivering blanks over said support, said means comprising four traveling pins spaced to engage both front and rear 115 edge portions of the blanks on said support.

10. A machine of the character described 120 comprising folding mechanism and means for delivering blanks thereto in accurate positions, said means comprising carriers having four pins spaced to engage each blank at four 125 separate points, said pins being adjustably connected with their carriers to enable them to be adjusted lengthwise of the carriers.

11. A machine of the character described 125 comprising folding mechanism and means for delivering blanks thereto in accurate positions, said means comprising carriers having four pins spaced to engage each blank at four 130 separate points, said pins being adjust-

ably connected with their carriers to enable them to be adjusted lengthwise of the carriers, the carriers being adjustable laterally for blanks of different widths.

- 5 12. A machine of the character described, comprising folding mechanism and means for delivering blanks thereto in accurate positions, said means comprising a pair of endless pin carriers each having a plurality of
10 blank engaging pins, the pins being spaced

to engage each blank at two points of the front edge and two points of the rear edge.

In testimony whereof we have affixed our signatures, in presence of two witnesses.
